CLAIM

The ornamental design for a stylus pen with ball-point pen, as shown and described.

DESCRIPTION

FIG. 1 is a front perspective view of a stylus pen with ball-point pen showing my new design;

FIG. 2 is a front view thereof;

FIG. 3 is a right side view thereof;

FIG. 4 is a rear view thereof;

FIG. 5 is a top plan view thereof;

FIG. 6 is a bottom view thereof;

FIG. 7 is a view similar to FIG. 3 with the ball-point pen in the used position; and,

FIG. 8 is a view similar to FIG. 3 with the reset pin in the used position.
